UNITED STATES PATENT OFFICE.

WILLIAM MASON, OF HARTFORD, CONNECTICUT, ASSIGNOR TO THE COLTS PATENT FIRE-ARMS MANUFACTURING COMPANY, OF SAME PLACE.

BREECH-LOADING FIRE-ARM.

SPECIFICATION forming part of Letters Patent No. 247,375, dated September 20, 1881.

Application filed May 21, 1881. (No model.)

To all whom it may concern:

Be it known that I, WM. MASON, of Hartford, in the county of Hartford, and State of Connecticut, have invented a new Improvement 5 in Breech-Loading Fire-Arms; and I do hereby declare the following, when taken in connection with the accompanying drawings and the letters of reference marked thereon, to be a full, clear, and exact description of the same, 10 and which said drawings constitute part of this specification, and represent, in—

Figure 1, a sectional side view, showing the parts in their normal condition; Fig. 2, same, showing the hammer as cocked; Fig. 3, detached view.

This invention relates to an improvement in that class of arms in which the barrel or barrels are hung forward, and so that the breech end tips up to open the cartridge-chamber, 20 and known as "barrel tilting up at the breech," and with special reference to what are known as "concealed hammers"—that is to say, the hammer arranged within the receiver of the arm and cocked in the act of tilting the barrels.

The invention consists in a rock-shaft arranged beneath the barrels, transversely thereto, and substantially the axis upon which the barrels turn, and in connection with the barrel, so that as the barrels are tilted the rock-shaft will turn upon its axis, combined with 30 a lever pivoted between the hammer and shaft, one arm of the lever in connection with the rock-shaft forward of its pivot, so that raising the breech end of the barrels depresses the forward arm of the lever, the other arm of the lever in connection with the hammer forward of its pivot, so that as the breech end of the barrel is raised the hammer is turned to full-cock, as more fully hereinafter described.

A represents the frame of the receiver, extending forward beneath the barrels B, as at C, the forward end rounded to receive the forearm D, in substantially the usual manner. In a recess in the receiver the hammer E is hung 45 upon a pivot, a, the upper end or nose arranged to strike a firing-pin, b; or it may be constructed with a projection which will pass through an opening in the breech end of the receiver to strike the primer.

F is a transverse rock-shaft arranged at the

forward end of the receiver, beneath the barrel, and forming, substantially, the axis on which the barrels turn in tilting. On the said rock-shaft a cam-like projection, f, is formed upon the upper side, and a similar cam-projection, h, below, and on the under side of the barrel a projecting lug, l, is formed to hook over the rock-shaft, its front surface engaging the cams f h, as shown, so that when the barrels are tilted the surface of the lug above the pivot bears against the cam f and turns the rock-shaft forward; then, in returning the barrels, the surface of the lug on the other side bears upon the cam h and turns the rock-shaft in the opposite direction. Between the rock-shaft and the hammer a lever is hung upon a pivot, n, one arm, H, extending forward through an opening, m, in the rock-shaft, so as to take a bearing in the opening or cavity forward of the center of the rock-shaft. The other arm 60 extends rearward, terminating in the shape of a stirrup, r, (see Fig. 3,) to engage beneath the arm P, which extends forward from the hammer, and so that the engagement of that arm L of the lever will be forward of the pivot 65 of the hammer.

The mainspring t is of the usual V shape, one end, d, resting against the under side of the arm L of the lever, near the hammer, the other end, e, hung to the arm P of the hammer. 70 Preferably the opposite or doubled end, s, is seated in a bearing on the under side of the lever, near its pivot.

The operation of this arrangement is as follows: When the barrels are tilted the rock-shaft turns as first described, and because the bearing of the arm H is forward of the center of the shaft it depresses that arm and raises the arm L, which lifts upon the arm P of the hammer, turning the hammer to full-cock, as 85 seen in Fig. 2. In this movement of the lever it will be observed that the bearing-point d of the mainspring is raised with the lever, but to a less extent than is the end e of the spring, which is in connection with the hammer; hence 90 the spring has been compressed only to the extent that the end e has been raised. When the barrels are returned to their closed position the lever returns also to its normal position, as seen in Fig. 2, broken lines. In this movement the 95 100

arm *d* of the spring will be forced toward the other arm, thus completing the application of the full force of the spring to the hammer for its blow when released. This arrangement of 5 the lever and spring distributes the power of cocking the hammer over both the opening and closing movements.

Instead of seating the doubled end of the spring in the lever, as at *s*, the other end, *d*, 10 may be engaged with the lever so as to retain its place without connection at the doubled end; or instead of applying the mainspring between the lever and the hammer, the main-spring may be applied directly to the hammer 15 independent of the lever.

It will be understood by those skilled in the art that, while specially intended for double-barreled arms, this invention may be applied to single-barrel arms.

20 In another application for patent, filed May 12, 1881, I have shown the rock-shaft arranged in the same manner as in this application, but with a different intermediate mechanism.

I therefore do not in this application make 25 broad claim to the transverse rock-shaft rotated by the opening and closing movements of the barrel to cock the hammer; but

What I do claim is—

1. In fire-arms in which the breech is opened 30 by the barrel tilting up at the breech, the combination therewith of a transverse rock-shaft arranged substantially at the axis upon which the barrel turns, an extension from the barrels into connection with said rock-shaft, so that 35 as the barrels are tilted said shaft will be turned, and a hammer hung at the rear, with a lever be-tween said rock-shaft and hammer, one arm of which engages with said rock-shaft forward of its center, the other arm of said lever engag- 40 ing with the hammer forward of its pivot, whereby the rotation of said rock-shaft in the act of tilting the barrels turns the rock-shaft and cocks the hammer, substantially as de-scribed.

45 2. In fire-arms in which the breech is opened

by the barrel tilting up at the breech, the combination therewith of a transverse rock-shaft arranged substantially at the axis upon which the barrel turns, an extension from the barrels into connection with said rock-shaft, so that 50 as the barrels are tilted said shaft will be turned, a hammer hung at the rear, with a lever be-tween said rock-shaft and hammer one arm of which engages with said rock-shaft forward of its center, the other arm of said lever engag- 55 ing with the hammer forward of its pivot, whereby the rotation of said rock-shaft in the act of tilting the barrels turns the rock-shaft and cocks the hammer, and a mainspring one end of which bears upon the arm of the lever 60 near the hammer, the other end of the spring engaging the hammer forward of its pivot, substantially as described.

3. In fire-arms in which the breech is opened by the barrel tilting up at the breech, the combination therewith of a transverse rock-shaft arranged substantially at the axis upon which the barrel turns, an extension from the barrels into connection with said rock-shaft, so that as 65 the barrels are tilted said shaft will be turned, a hammer hung at the rear, with a lever be-tween said rock-shaft and hammer, one arm of which engages with said rock-shaft forward of its center, the other arm of said lever engag- 70 ing with the hammer forward of its pivot, whereby the rotation of said rock-shaft in the act of tilting the barrels turns the rock-shaft and cocks the hammer, and a mainspring one end of which bears upon the arm of the lever 75 near the hammer, the other end of the spring engaging the hammer forward of its pivot, the doubled end of the spring seated on the lever 80 near its pivot, substantially as described.

WILLIAM MASON.
